UNITED STATES PATENT OFFICE.

MINERVA R. BUCKLEY, OF FORT SCOTT, KANSAS.

AUTO DRESS.

1,421,162.

Specification of Letters Patent. Patented June 27, 1922.

Application filed June 29, 1920. Serial No. 392,856.

To all whom it may concern:

Be it known that I, MINERVA R. BUCKLEY, a citizen of the United States, residing at Fort Scott, in the county of Bourbon and 5 State of Kansas, have invented new and useful Improvements in Auto Dress, of which the following is a specification.

My present invention pertains to apparel, and it contemplates the provision of a garment that may be worn to protect clothing from dust and dirt, and this with equal 10 facility by a man or woman.

The invention has for one of its objects 15 the provision of an overall or body covering for use by occupants of an automobile to prevent dust and the like from gathering on the garments of the wearer, especially when necessary, to make repairs, change tires and the like, on a trip.

20 The invention also contemplates the provision of a garment that may be so adjusted over the garments of a woman that her skirts will be prevented from hampering her in her free movements during house 25 work and the like.

The invention in all its details will be 30 fully understood from the following description and claim when the same are read in connection with the drawings, accompanying and forming parts of this specification, in which:

Figure 1, is a view in elevation of the garment and showing the rear thereof as unbuttoned preparatory to being donned.

35 Figure 2, is a rear perspective view of the garment and showing how the same appears when fastened in one position.

Figure 3, is a view similar to Figure 2 and showing how the garment appears when 40 fastened in another position.

Figure 4 is a detailed view of the garment and showing the manner of fastening the same at the rear thereof.

45 Figure 5 is end section of Figure 4.

Similar numerals of reference designate

like parts in all the views of the drawings.

My novel garment comprises the body 50 portion 1 that is open down its full length in the rear thereof, and is faced as indicated by 2. This facing 2 is provided with male fasteners or snappers 4 and directly opposite said fasteners are female fasteners 3 whereby the entire opening in rear of the garment may be closed.

55 In the rear of the garment is a split or short opening that is provided with a facing

5 and fasteners of the male and female variety 6 as indicated.

The body 1 may be provided with the upper portion 7 that is secured to the belt 8 60 and said portion 7 is provided with shoulder straps 9 at one end of which are male fasteners that enter the female fasteners 11 of the belt 8.

In the practical use of the garment the 65 same is secured about the ordinary dress or other wearing apparel in the manner shown in Figure 2.

However, when occasion demands the leg 70 portions shown in Figures 3, 4 and 5 may be produced, insuring greater protection and greater facility in working, by simply opening the split in rear of the garment and unbuttoning the first two fasteners in front of the garment and then fastening the front 75 and rear portions together at the left in Figure 1 and the front and rear portions at the right in said figure, together, to produce the garment shown in Figures 3, 4 and 5.

80 It will be understood from the foregoing that the garment is simple and inexpensive to produce and may be worn with the greatest of comfort and facility, especially by women who operate and do certain repairs 85 on their automobiles as the same may be worn buttoned between the ankles as illustrated in Figure 3 and 4, and this with but slight effort on the part of persons practicing the invention.

90 Moreover, the garment when worn as illustrated in Figures 3 and 4 will effectually preclude dust and dirt from the skirts of a woman automobilist and permit ready and easy movement of her feet without liability of her skirts coming in contact with the clutch or other mechanism of a vehicle. It offers further protection to the waist 95 of wearer, at the back, from becoming soiled from perspiration and dirt from the back of car seat.

Having described my invention, what I claim and desire to secure by Letters-Patent is:—

In a garment, the combination of a bib 105 portion, shoulder straps secured to the bib portion, a skirt portion stitched at its front to said bib, a longitudinal placket formed in the rear of the skirt portion, button-holes formed on one face of the material of the 110 skirt adjacent the opening and buttons secured on the opposite face, whereby the

opening may be closed to form a skirt, a comparatively short placket formed in the front of the skirt and extending from the the hem thereof, buttons secured on one 5 face of the placket and button-holes formed on the opposite face thereof, whereby the placket may be closed or whereby several buttons of the rear placket may engage the button-holes of the short placket and the 10 buttons of the short placket may engage

several button-holes of the rear placket to form leg portions at the lower end of the skirt.

In testimony whereof I have hereunto set my hand in presence of two subscribing witnesses.

MRS. MINERVA R. BUCKLEY.

Witnesses:

Mrs. W. C. OLDS,
LILA SMITH.
